UNITED STATES PATENT OFFICE.

THEODORE H. SCHUTT, OF CLEVELAND, OHIO, ASSIGNOR TO THE RUSS COMPANY, OF CLEVELAND, OHIO, A CORPORATION OF OHIO.

SELF-CLOSING FAUCET.

Application filed June 9, 1919. Serial No. 302,840.

To all whom it may concern:

Be it known that I, THEODORE H. SCHUTT, a citizen of the United States, residing at Cleveland, in the county of Cuyahoga and 5 State of Ohio, have invented certain new and useful Improvements in Self-Closing Faucets, of which the following is a specification.

This invention relates to self-closing 10 faucets, such as are used for drawing off water or other liquids into a drinking glass or other receptacle. The invention has particular relation to that class of faucets in which the controlling valve is actuated by 15 the receptacle to be filled.

One object of the invention is to provide a self-closing faucet the operating mechanism for which is engaged for actuation by the side instead of by the rim or edge of 20 the drinking glass or receptacle, so that the device is sanitary and there is no danger of contaminating a succeeding receptacle from deposits on the operating mechanism from a preceding receptacle.

25 A further object of the invention is to provide simple valve mechanism which avoids the use of springs and may also dispense with packings, and which is simple to construct, inexpensive to manufacture, 30 and is not liable to get out of order in service.

Further objects of the invention are in part obvious and in part will appear more in detail hereinafter.

35 The invention comprises the construction and arrangement of parts hereinafter described and claimed.

In the drawings, which represent one embodiment of the invention, Fig. 1 is a side 40 elevation; Fig. 2 is a sectional elevation on the line 2—2, Fig. 1; and Fig. 3 is a sectional elevation on the line 3—3, Fig. 2.

The device shown in the drawings comprises a suitable hollow fitting adapted for 45 connection to the reservoir or the device from which the liquid is to be withdrawn. This reservoir may be a tank, water cooler, or other device (not shown), or the valve may be connected directly to a service line.

50 As illustrated the fitting is provided with the usual shoulder 2 to seat against the outside of the reservoir and a threaded connection 3 for entering an opening in said reservoir. At its opposite end the fitting is externally threaded to receive the threaded

end 4 of the faucet body 5, which is of hollow form with a cross wall 6 therein dividing the cavity in the body into a pressure chamber 7 communicating with the supply fitting and a discharge chamber 8. A portion of the wall 6 is horizontal as shown in Fig. 3 and is provided with a valve seat surrounding an opening 9 through said wall. The valve seat, for example, may be formed by a fiber or other washer 10 fitted to a recess in the wall. Cooperating with said seat is a valve member, shown as an annular flange 11 carried by a stem 12. The upper portion of said stem slides in a pocket 13 in a cap 14 fitted to the top of the valve body, while the lower end of the stem 15 extends through the port or opening 9 and serves as a push rod for opening the valve.

The outlet from the discharge chamber 8 is through a nozzle 16 threaded into the bottom of the valve body and having a vertically extending opening 17 to direct the stream downwardly.

At one side the valve body is enlarged, as at 18, said enlarged portion being hollowed out to form therein an extension 19 of the discharge chamber 8. The enlargement 18 is also pierced horizontally through the chamber extension 19, and in the opening thus formed is located a shaft 20. The inner end portion of said shaft rests in a pocket or recess 21 of the valve body and is non-circular in cross section, such as by being provided with a flattened portion 22, to receive the eye 23 of a lever lying in the chamber extension 19 and having an arm 24 extending beneath the push rod 15. The outer end of the shaft 20 extends through an adjacent wall of the casing or body. At the opposite end of the enlargement 18 the body is provided with a trunnion of substantially the same diameter as the shaft 20, and which, for example, may be a screw 25 threaded into an opening in the casing or body and whose head is of cylindrical form.

100 The valve mechanism is operated by a lever 26 bifurcated at its upper end to form a yoke comprising two arms 27 each of which has an eye at its upper end. The eye of one of said arms turns on the trunnion 25, while the eye of the other arm is secured to turn with and actuate shaft 20, such as by being secured to said shaft by a screw 28. The lower end of said lever extends forwardly and is preferably provided with a 110

cross arm 29 which, in normally closed position of the parts, lies fairly close to the central vertical axis of the device.

The full lines in Fig. 3 represent the normal position of the parts. Valve 11 is held to its seat by the pressure of the incoming liquid in the pressure chamber 7. Operating arm 26 is swung forwardly on its pivot at the shaft 20, its forward movement being limited in any suitable manner, such as by engagement of said arm with a fixed part of the casing, such as with the nozzle 17, as indicated at 30. In drawing water from the faucet the drinking vessel, such as a glass, is held in the hand and pushed into position beneath the outlet portion 17 as shown in the dotted lines, Fig. 3. This motion pushes back the arm 29 and turns the lever 26 in a counter-clockwise direction, thereby turning shaft 20 and lifting the valve 9 from its seat. The drinking vessel does not touch the valve mechanism or body except at its side and some distance away from its rim, so that it cannot be contaminated. When the drinking vessel is withdrawn the lever 26 returns to its original position by gravity and the valve is closed by the supply pressure.

No packing is necessary around the shaft 20, which passes through the discharge chamber and not through the pressure chamber. However, if desired, said shaft at one or both ends may be packed to prevent en-

trance of air to the discharge chamber such as might break up the otherwise solid discharge stream. As illustrated the opening in which the shaft turns is closed at one end by the screw 25, whose head is provided with a shoulder which can be turned up tight against the outside of the casing. At its other end the shaft may be provided with a packing 31 compressed by a nut 32 surrounding said shaft and threaded into the casing.

What I claim is:

A self-closing faucet, comprising a casing provided with pressure and discharge chambers, a valve controlling the flow of liquid from the pressure to the discharge chamber, a shaft rotatable in the casing and having a portion lying in the discharge chamber and operatively associated with said valve, a yoke member for engagement by the side wall of a receptacle, one arm of said yoke member being fixedly mounted on one end of said shaft, the other end of said shaft having rotatable bearing in the wall of said casing, and a trunnion fixed in the wall of said casing and affording bearing for the other arm of said yoke member.

In testimony whereof I affix my signature in presence of two witnesses as follows:

THEODORE H. SCHUTT.

Witnesses:

ROLAND KRAUS,
C. LUNDBERG.
